UNITED STATES PATENT OFFICE.

CLARENCE S. SLATCHER, OF PHILADELPHIA, PENNSYLVANIA.

SHOWER-BATH APPARATUS.

Specification of Letters Patent. Patented Jan. 10, 1922.

1,402,974.

Application filed June 18, 1921. Serial No. 478,513.

To all whom it may concern:

Be it known that I, CLARENCE S. SLATCHER, a citizen of the United States, residing at Philadelphia, in the county of Philadelphia, and State of Pennsylvania, have invented certain new and useful Improvements in Shower-Bath Apparatus, of which the following is a specification.

My invention relates to certain new and useful improvements in shower-bath apparatus; and its object is to produce a device of this class which shall have certain advantages which will appear more fully and at large in the course of this specification.

The primary object of the invention is to provide a separable tubular perforated ring adapted to be positioned within the conventional type of bath tub and connected to the usual faucet of said tub, whereby the bather may spray water upon himself while recumbent in the tub.

A further object of the invention is to provide means in a device of the class described, whereby the bather may, if desired, shut off that portion of the spray playing upon his head or back, without impeding the flow of the balance of the spray or shower.

To these ends the invention consists in various details of construction and combinations of parts, all of which will be hereinafter more fully described and particularly pointed out.

In the drawings:

Figure 1 is a plan view of a bath tub with my improved separable shower-bath apparatus in place;

Figure 2 is a vertical longitudinal sectional view on line 2-2 of Fig. 1;

Figure 3 is a transverse sectional view on line 3-3 of Fig. 2; and

Figure 4 is a perspective of the separable shower-bath device.

Referring now more particularly to the several figures of the drawings wherein similar reference characters indicate like parts in all of the views, the numeral 10 represents a conventional form of bath-tub, having the usual feet 11 for spacing it above the floor, a substantially vertical foot 12, side walls 13-13, flaring slightly, and a head 14 sloping at a considerable angle, as bath tubs are ordinarily made.

The tub 10 is fitted with a Siamese faucet 15, i. e., a faucet of the type where the

hot and cold water pipes meet at the center of the faucet and pass down in a single stream, through an outlet nipple 16 to said faucet 15.

My improved shower-bath apparatus, designated in its entirety by the numeral 17, comprises, substantially, a tubular ring having a curved head end 18, longitudinally extending side portions 19 and 20, extending parallel with each other, and a transverse foot portion 21. Said tubular ring 17 is adapted to fit within the conventional type of bath tub 10, substantially, at the height of the longitudinally extending pipe connections 15' and 15² of the faucet 15 to the sources of hot and cold water supply, the said transverse portion 21 of the tubular ring 17 resting upon the said pipes 15' and 15². The opposite curved end 18 of the ring 17 being supported entirely by engagement with the slanting head 14 of the tub 10.

The longitudinal extending parallel side portions 19 and 20 of the ring 17 are provided with the perforations 22 as shown and the curved end 18 of the ring 17 is provided, in the central portion thereof, with like perforations 23. A downwardly extending nipple 24 is provided, substantially, in the center of the transverse portion 21 of the ring 17.

A split tubular collar 25 having the perforations 26 is provided to fit over the perforated portion of the end section 18 of the ring 17. A knob or button 27 is provided on the collar 25 so that the perforations 26 and 23 may be brought in and out of communication.

A hose connection 28 is provided to connect the nipple 16 on the faucet 15 with the nipple 24 on the transverse section 21 of the ring 17.

In view of the following description it will be seen that I have provided an extremely simple construction, wherein the continuous pipe contacts with the inner walls of the tub, and are supported thereby, and all auxiliary supporting means for the pipe are dispensed with. At the forward end or portion of the curved portion 18, the pipe 105 is in the form of a straight portion, which is spaced from the head or wall of the tub, providing a pocket or clearance. This straight portion has apertures, and slidably receives the pivoted sleeve 25, having the

apertures 26. The spacing of the straight portion of the curved portion 18, affords a space for the sleeve 25.

The operation of my improved shower device will be readily apparent. When the water is turned on in the faucet 15 it will flow through the connection 28 from the nipple 16 on said faucet 15 to the nipple 24 and into the tubular ring 17 and issues from the perforations 22 in the longitudinal side portions 19 and 20 and the perforations 23 in the end section 18 of the tubular ring 17 in the form of a fine spray 29.

If the occupant of the tub does not want the shower to play upon his head, or to issue through the perforations 23 in the end or head section 18 of the ring 17, the knob or button 27 can be turned so that the perforations 26 and 23 do not communicate, therefore

20 by shutting off the shower at this point. The improved shower device just described can be readily attached and detached to and from the usual type of faucet 15 at the will of the bather, and when not in use can either be removed from the tub, or it can remain in position, disconnected, without interfering with the use of the tub. Flexible metallic tubing may be used in place of the hose 28, if desired.

30 It will now be apparent that I have devised a novel and useful construction which embodies the features of advantage enumerated as desirable in the statement of the invention and the above description, and 35 while I have in the present instance shown and described the preferred embodiment thereof which has been found in practice to

give satisfactory and reliable results, it is to be understood that the same is susceptible of modification in various particulars 40 without departing from the spirit and scope of the invention or sacrificing any of its advantages.

Having thus described my invention what I claim as new and desire to secure by Letters Patent is:—

The combination with an ordinary bath tub having sides and an inclined head portion and a spigot at the foot portion of the tub, of a substantially horizontal continuous pipe embodying side portions connected at their forward ends by a curved transverse head portion, said curved head portion having a straight intermediate portion which is spaced from the inclined head portion of the tub providing a passage while the side portions and curved portions of the pipe contact with the inner walls of the tub, said straight intermediate portion being provided with apertures and the side portions 60 having apertures, said pipe further including a transverse foot portion connecting the side portions and resting upon the spigot to be supported thereby, the forward end of the pipe being entirely supported by contact between the same and the walls of the tub, and an apertured sleeve pivotally mounted upon the straight intermediate portion and operating in said passage, and means for connecting the transverse foot 70 portion with the spigot for supplying water to said transverse foot portion.

In testimony whereof I affix my signature.

CLARENCE S. SLATCHER.
